[57] CLAIM

The ornamental design for a combined food product and support board therefor, as shown and described.

DESCRIPTION

FIG. 1 is a top plan view of the combined food product and support board therefor showing our new design;

FIG. 2 is an end view thereof;

FIG. 3 is an opposed end view;

FIG. 4 is a left side elevational view thereof, the opposite side being a mirror image thereof;

FIG. 5 is a right side elevational view thereof; and

FIG. 6 is a top plan view of a second embodiment of FIG. 1 thereof having two colors, it being understood that the undisclosed sides and bottom are the same as in the first embodiment; and,

FIG. 7 is a top plan view of a third embodiment of FIG. 1 thereof having a "U" shaped support board it being understood that the undisclosed sides and bottom are the same as in the first embodiment and that the undisclosed bottom of embodiments 1, 2, and 3 of the claimed article is flat and plain.
